UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FASTENER.

1,156,004.

Specification of Letters Patent.

Patented Oct. 5, 1915.

Application filed February 23, 1915. Serial No. 9,817.

To all whom it may concern:

Be it known that I, FRANZ A. FULLER, a citizen of the United States, residing in the city of Newark, in the county of Essex and State of New Jersey, have invented certain new and useful Improvements in Bag-Fasteners, of which the following is a full, clear, and exact description, such as will enable others skilled in the art to which it pertains to make, construct, and use the same, reference being had to the accompanying drawings, and to letters of reference marked thereon, forming a part of this specification.

The present invention has reference to improvements in that class of bag fasteners for bag frames which are especially adapted for pocket books, satchels, purses and the like, and the invention relates more fully to a novel construction of a locking or holding catch connected with the frame sections thereof.

The main purpose of this invention is to provide a pocket book, purse or other frame section, with an auxiliary latch or catch which shall be neat in appearance, and shall be of a simple, strong and durable construction, with the view of additionally holding the frame members together and independently operated from the fastener.

With this object of my invention in view, the same consists in a novel bag fastener hereinafter set forth, and furthermore, this invention consists in the various arrangements and combinations of the parts thereof, all of which will be fully described in the accompanying specification, and then finally embodied in the clauses of the claim thereof, which are appended to and form an essential part of this specification.

In carrying out my invention, I make use of the structure illustrated in the accompanying drawings, in which—

Figure 1 represents a front elevation of a bag frame showing my improved fastener secured thereto. Fig. 2 represents an enlarged longitudinal sectional side elevation taken on line $x-x$ of Fig. 3, looking in the direction indicated by the arrow. Fig. 3 represents an enlarged vertical section of the frame members taken on line $x-x$ of Fig. 1, the fastener on the top of the sec-

tions not being shown. Fig. 4 represents an enlarged longitudinal sectional side elevation taken on line $y-y$ of Fig. 3, looking in the direction indicated by the arrow. Figs. 5 and 7, and 6 and 8 represent respectively, vertical and longitudinal sections of modified forms of my improved fastener; and Fig. 9 represents a modified form of spring.

Similar letters of reference refer to like parts throughout the specification and drawings.

A bag frame fastener made in accordance with my invention, may be applied to any ordinary or desired form of frame. That shown in the drawings consists of two hinged frame members a and b , of substantially the shape shown in Fig. 3. Near the middle portion of the frame member a , I secure a fastener or catch c , of any desired form or configuration, and in any desired manner, designed to be brought into holding engagement with a suitable nosing or projection formed on the frame member b , to firmly secure the bag frame sections or members in locked position. The middle portions of the frame members a and b form receiving pockets, one of which serves to receive the novel spring of my improved fastener.

The improved fastener consists of a latch stud e mounted to turn in suitably-aligned apertures formed in the frame member b , which is preferably made from cylindrical metal rod, the outer end being provided with an annular flange f , which bears against the outside of the frame member b and serves to limit the inward movement of the latch when it is being assembled. A pull piece g , as for instance, a ring, loop or the like, is pivotally secured to an integral extension formed on the latch stud e to facilitate manipulation, and a reduced latch-head i formed on the opposite or inner end of the stud is designed to pass through a suitable aperture formed in the frame member a to have holding engagement therewith, for additionally holding the frame members a and b together.

The latch stud e is controlled and held in position by a spring, comprising two members lettered respectively j and k , so

formed that it is actuated by the flattened portions $l-l$ formed on the stud and located between the flanges $m-m$, by means of which the stud is rotatively secured to the 5 frame member b .

Both of the spring members j and k are formed from a single flat piece of metal, of approximately the width of the inside of the channeled frame member b , and of 10 a length to be received into the receiving pocket of the said frame member. The member k is centrally chambered as illustrated, and is provided with the integral inturned ends n , said ends being designed to receive 15 the ends of the member j , as clearly indicated, and by means of which the members are held together in their operative position. One end of the member j is provided with an offset portion o , said offset portion acting 20 as a stop to limit the movement of the said spring member j and to prevent accidental displacement of the two members when once assembled.

In assembling the device, the member k is first placed into the receiving pocket of the frame member b , and the latch stud e is inserted through the alined apertures in said frame member, with one of the flattened portions l of the stud bearing against the 25 spring member k . The offset portion o of the spring member j , is then inserted as far as possible into the inturned end n of the spring member k , so as to permit the free end of the spring member j to be sprung 30 under and shoved forward into engagement with the opposite inturned end n of the spring member k , when the offset portion o of the spring member j will engage with the inturned end n , as clearly illustrated in 35 Fig. 5 of the drawings.

By turning the pull-piece g in either direction, the latch stud e with its flattened portions, will actuate the spring members j and k , so as to cause the latch-head i to become 40 either engaged or disengaged from the aperture formed in the frame member a .

The construction and arrangement of the spring members j and k are such as to exert a downward pressure upon the latch stud e , 45 to maintain the latch in its locked position, and in order to enable the latch-head i to freely enter and engage with the aperture p in the frame member a , I cut away a portion of the flange m , nearest the latch head, 50 as at q , (see Figs. 2, 3 and 4) so that when the two frame members a and b are brought together with the latch head i in the position shown in Fig. 3 of the drawings, the beveled portion of said latch head will engage 55 with the under side of the aperture p in the frame member a , and owing to the clearance above the cut-away portion q of the flange m and the top edge of the aperture in the frame member b in which it is 60 located, the latch stud e will be enabled to 65

exert an upward pressure against the spring member k and be raised sufficiently to enable the latch head i to freely pass over the lower edge of the aperture p in the frame member a , the lower edge of the aperture p not being in alinement with the lower edge of the aperture in the frame member b , but above it, so that the spring k can exert its downward pressure to force the latch-head i into locking engagement with the frame member a . 70 75

In the modified form illustrated in Figs. 5 and 6 of the drawings, I secure within the channel of the frame section a a flat spring r , which may be secured thereto in any convenient or desired manner, the spring r being provided with an aperture s designed to receive and have holding engagement with the latch-head i , which in this case, is made longer than the one illustrated in Fig. 3 of the drawings. The aperture s in the spring r enables the beveled latch head i to pass therethrough, and to have holding engagement therewith, in substantially the same manner that the latch-head i passes through 90 the aperture p in the frame member a , as illustrated in Fig. 3 of the drawings. In this construction, the alined apertures in the frame members a and b are of substantially the same shape and size, but the aperture in 95 the spring r is not in alinement with the apertures in the frame sections a and b .

In Figs. 7 and 8 of the drawings, the apertures in the frame sections a and b are in alinement, but the flange m nearest the latch-head i is not cut away, as illustrated in Figs. 3 and 5 of the drawings, and a flat spring t is secured within the channel of the frame member a , the lower edge of which is designed to be engaged by the beveled portion 105 of the latch-head i , when the frame sections a and b are brought together, in order to have locking engagement therewith.

To permit of the upward movement of the latch stud, Fig. 7 of the drawings, I elongate the aperture in the frame member b near the latch-head i , and above the stud, as clearly indicated. I have also shown the spring member k , Fig. 4 of the drawings, at its chambered portion, with a pair of integrally-formed depending lugs, the inner surfaces of which are adapted to engage with the latch stud e . It is of course to be understood that the lugs may be dispensed with on the spring member k and similar 110 lugs provided on the spring member j , by means of which the spring members are properly positioned and operatively held in the receiving pocket of the frame section b . 115

The modified form of spring u illustrated 120 in Fig. 9 of the drawings, consists of but one member, the central or chambered portion of which is provided with a pair of integrally formed depending lugs w , the inner surfaces 125 of which engage with the latch stud e , and 130

by means of which the spring *u* is positioned and operatively held in the receiving pocket of the frame section *b*.

The fastener just described, serves for additionally holding the frame members *a* and *b* in locked position, and is independently operated from the fastener or catch *c*.

The invention is not limited to the exact embodiment shown, but may be modified in various ways in the scope of the following claims.

I claim:

1. In combination with a bag frame, a latch stud mounted to turn in one member of said frame, and provided with a latch-head adapted to engage the other member of the said frame, said latch stud being further provided with means in engagement with the frame member in which it is mounted, for permitting upward movement of said latch stud, and a spring for controlling the movements of said latch stud.

2. In combination, two frame members movable relatively to each other, a spring-actuated locking device rotatively secured in one of said frame members, comprising a latch stud provided with a latch-head adapt-

ed to engage with the other frame member to have locking engagement therewith, said latch stud being further provided with a cut-away portion, said cut-away portion being in engagement with the frame member in which it is mounted, for permitting upward movement of said latch stud, and a spring for controlling the rotary and upward movement of said latch stud.

3. In combination, two frame members movable relatively to each other, a spring-actuated locking device rotatively secured in one of said frame members, comprising a latch stud provided with a latch-head adapted to engage the other frame member to have locking engagement therewith, the first-named frame member being provided with means for permitting upward movement of said latch stud, and a spring provided with positioning means for controlling the movement of said latch stud.

This specification signed and witnessed this 12th day of February, 1915.

FRANZ A. FULLER.
